HIGH VOLTAGE SWITCH

John B. Shaw, San Francisco, Calif., assignor to
 Pacific Electric Manufacturing Corporation,
 San Francisco, Calif., a corporation of California

Application April 26, 1943, Serial No. 484,509

5 Claims. (Cl. 200—48)

My present invention relates to disconnecting switches, and particularly to disconnecting switches of the type having a flattened or beavertail end that is adapted to be turned about the longitudinal axis of the switch blade and bring oppositely disposed contact surfaces at the end thereof into high pressure contact making engagement with the opposed faces of a cooperating stationary contact.

An object of the invention is to provide an operating mechanism for a disconnecting switch of the above type in which the circuit opening and closing movements of the switch blade and the contact pressure establishing rotary movements thereof are produced in a novel, efficient and practical manner.

Another object of the invention is to provide an operating mechanism for a pivotally mounted disconnecting switch blade of the type that is rotatable into and out of contact making engagement with a stationary contact when the switch blade is in its closed circuit position, in which substantially all of the rotary movement of the switch blade occurs prior to any pivotal circuit opening movement thereof or subsequent to any pivotal circuit closing movement thereof with respect to its cooperating stationary contact.

Another object of the invention is to provide an improvement in a disconnecting switch of the character described having a pivotally mounted blade that moves into cooperating relation to a stationary contact with a swinging and rotating movement, in which the blade operating forces are transmitted from a rotatable insulator stand to the pivotally mounted switch blade through an operating mechanism that will limit the rotating movements of the switch blade to a point substantially at the beginning and at the end of its pivotal circuit opening and circuit closing movements.

A further object of the invention is to provide an operating mechanism for a disconnecting switch of the character described in which there is provided a blade rotation imparting connection that will produce a greater blade rotation at the proper time than is possible with the corresponding operating devices of the prior art.

In the art to which my present invention relates there are a number of types of operating mechanisms for disconnecting switches of the character contemplated. In each of these types, in addition to swinging the switch blade between its open and closed circuit positions, the operating mechanism also imparts rotation to the blade for the purpose of bringing contact engaging surfaces at the end thereof into high pressure engagement with a stationary contact of proper design. In the prior art arrange-

ments resort has generally been had to an overtravel of the operating insulator column in order to complete the high pressure contact. While this overtravel limits, to a degree, the

5 swinging movement of the switch blade during its rotative movement, due to the inherent characteristics of these operating mechanisms, unless there is provided considerable play or looseness in the operating mechanisms, the switch 10 blade must necessarily start its swinging movement at the same time that its rotary movement is initiated. Therefore, special precautions are taken by providing suitable stops which operate to hold the switch blade against any swinging 15 movement as its operating mechanism operates to impart the desired rotary movement to the switch blade as it is moved out of and into cooperating relation with the stationary contact.

20 To overcome the above disadvantages, I have provided an operating mechanism in which the blade swinging and rotating forces are transmitted from a rotatable insulator column through a link-like operating connection that 25 will impart a maximum of swinging movement to the switch blade and, at the same time, limit the rotative high pressure contact making movement of the blade to a period in its operation when the switch blade is in its closed circuit 30 position adjacent the stationary contact with which it cooperates.

Other objects and advantages of my invention will be in part evident to those skilled in the art and in part pointed out hereinafter 35 in the following description taken in connection with the accompanying drawing, wherein there is shown by way of illustration and not of limitation preferred embodiments of the invention.

In the drawing:

40 Figure 1 is a side elevation showing a disconnecting switch, constructed in accordance with a preferred embodiment of the invention, in its circuit closed position.

Figure 2 is a plan view of the disconnecting 45 switch shown in Figure 1.

Figure 3 is a fragmentary view showing the position of the operating mechanism when the switch blade is in its full open circuit position.

50 Figure 4 is a fragmentary end view showing the position of the blade, with respect to its cooperating stationary contact, when the switch blade is in its closed circuit position, and

55 Figure 5 shows the position of the switch blade immediately prior to an initial circuit opening operation thereof, or just prior to a final circuit closing operation thereof.

As will be seen from an inspection of the accompanying drawing, the switch blade and operating mechanism contemplated by my inven-

tion is mounted in the conventional manner upon three insulator columns 10, 11 and 12 that are held in properly spaced relation upon a suitable support 13. The support 13, as here shown, may be the cross arm of a power line supporting pole or tower, or it may be in the form of a bracket upon a roof or wall of a building. It will also be understood that the supporting frame 13 may be disposed in a horizontal or a vertical position, depending upon its location. The insulator column 10 serves as a support for a stationary contact clip 14 with which there is associated a terminal 15 to which a conductor of the power line is connected, and the insulator column 11 carries a pivotally mounted support 16 upon which a tubular switch blade 17 is mounted. In this instance the switch blade 17 is adapted to rotate about an axially extending shaft or bearing 18 that is carried by the pivotally mounted support 16. At its outer end the switch blade 17 is flattened to provide a so-called beaver-tail end 19 which has laterally disposed contact surfaces at its edges that are adapted to be turned into high pressure contact engagement with the opposed contact surfaces of the stationary contact clip 14. Secured upon and extending radially from the switch blade 17 there is an arm or clevis-like extension 20 by means of which the switch blade 17 may be rotated, as will hereinafter appear.

The insulator columns 10 and 11 are fixed upon the supporting frame 13, and the insulator column 12 is journaled at its lower end within a bearing 21 so that it may be turned to operate the switch blade 17. At its upper end the insulator column 12 is journaled in the outer end of a strut 22 which carries a projecting terminal lug 23 to which the other conductor of the power line is connected. This strut 22 extends between the tops of the insulator columns 11 and 12 and serves to space these insulator columns in proper relation to each other. Adjacent the pivotal support 16 the strut 22 carries a flexible current conductor 24 which connects with the switch blade 17 and provides a current conducting path around the bearing surfaces upon which the switch blade 17 and the pivotal support 16 are mounted. In order to impart an operating movement to the insulator column 12, this latter insulator column carries a lever arm 25 that may be connected to a suitable operating mechanism and/or to an adjacent similar switch in the well known manner. Fixed upon the upper end of the insulator column 12 there is a substantially radially extending crank arm 26 that has a projecting spindle 27, and rotatably mounted upon the spindle 27 there is a swivel 28 which has two oppositely extending trunnions 29 to which the ends of a bifurcated link 30 are connected. At its other end the bifurcated link 30 is connected to the clevis-like extension 20 carried by the switch blade 17 by means of a universal joint connection 31. This universal joint connection 31 is here shown as adjustably connected to the bifurcated link 30. However, it will be understood that once this connection has been properly made, no further adjustment will be required. At this point it should be stated that while I have illustrated and described the operating link 30 as of bifurcated construction and as connected to the crank arm 26 by the swivel 28 having trunnions 29, it will be understood that the link 30 may take other forms. For example, it is contemplated that instead of the trunnions 29, the swivel 28 may be provided with outwardly

extending spaced ears between which this end of the operating link 30 may be connected in such a manner as to operate in accordance with the present invention.

With the switch constructed as above described, it will be understood that when the crank arm 26 is in its dead center position with respect to the axis of the switch blade 17, the trunnions 29 carried by the swivel 28 will extend in a horizontal direction with the clevis 20 upon the switch blade extending substantially vertical. When the parts are in this position, the bifurcated link 30 will have no tendency to turn the swivel 28 about its spindle 27 and, therefore, since the swivel 28 cannot turn in this position of operation to permit a hinging between the bifurcated link 30 and the crank arm 26, the bifurcated link 30 will form a substantially coextensive and rigid extension of the crank arm 26 and thus exert a substantially transversely applied force upon the clevis 20 that will cause the switch blade 17 to turn through a limited angle about its supporting shaft or bearing 18 which is carried by the pivotally mounted support 16. When the operating mechanism is in the position shown in Figure 1, the beaver-tail end 19 of the switch blade 17 will be in a substantially horizontal position, as shown in Figure 4 of the drawing, and as the above described force is transversely applied to the clevis 20, the beaver-tail end 19 of the switch blade 17 will assume a position substantially corresponding to that illustrated in Figure 5 of the drawing. Then, as the crank arm 26 continues to move around in a counter-clockwise direction, as viewed in Figures 2 and 3 of the drawing, the swivel 28 will turn about its spindle 27 and cause the bifurcated link 30 to exert a pulling force upon the clevis 20 which will cause the switch blade 17 to swing outwardly with its pivotal support 16 and into an open circuit position with respect to the stationary contact clip 14. During this switch opening operation, it will be understood that as the switch blade 17 swings into its open circuit position, the clevis 20 and the switch blade 17 will move around the axis of the extending shaft or bearing 18 and thus permit the necessary rotation of the swivel 28 upon its spindle 27, as shown in Figure 3 of the drawing.

While I have, for the sake of clearness and in order to disclose the invention so that the same can be readily understood, described and illustrated specific devices and arrangements, I desire to have it understood that this invention is not necessarily limited to the specific means disclosed, but may be embodied in other ways that will suggest themselves to persons skilled in the art. It is believed that this invention is new and it is desired to claim it so that all such changes as come within the scope of the appended claims are to be considered as part of this invention.

Having thus described my invention, what I claim and desire to secure by Letters Patent is:

1. In a disconnecting switch of the type having a rotatable blade, the combination of a stationary contact, a switch blade having laterally disposed contact surfaces at its end adapted to cooperate with said stationary contact, a pivotally mounted support for said switch blade adapted to permit a swinging movement of the switch blade into and out of cooperating relation with said stationary contact, a blade supporting shaft extending outwardly from said pivotally mounted support, an operating crank arm spaced from said pivotal support and supported to operate about

a vertical axis, a spindle carried by and extending outwardly at the end of said crank arm, a swivel member mounted to turn about said spindle and having oppositely extending trunnions, a bifurcated link having its bifurcations journaled upon the oppositely extending trunnions of said swivel member, an outwardly extending clevis-like extension carried by said switch blade, and a universal connection between said clevis-like extension and the extending end of said bifurcated link, whereby said switch blade will be turned about its supporting shaft when said bifurcated link and said operating crank arm are in coextending relation with respect to each other and will subsequently swing vertically with said pivotally mounted support when said link and said operating crank arm move into angular relation with respect to each other.

2. In a disconnecting switch of the type having a rotatable blade, the combination of a stationary contact, a switch blade adapted to cooperate with said stationary contact, a pivotally mounted support upon which said switch blade is rotatably mounted adapted to also permit a swinging movement of said switch blade into and out of engagement with said stationary contact, a crank arm positioned rearwardly of said pivotally mounted support and operating about a vertical axis, a swivel-like member carried by the outer end of said crank arm and rotatably mounted to turn about an axis substantially radial to the vertical axis about which said crank arm operates, said swivel-like member having oppositely extending trunnion forming projections, a bifurcated link having its bifurcations journaled upon the trunnion forming projections of said swivel-like member, whereby said bifurcated link and said operating crank arm will act as a rigid lever throughout one range of movement of said crank arm and hinge with respect to each other in another range of movement of the crank arm, an outwardly and upwardly extending clevis carried by said switch blade, and a universal connection between said clevis and the extending end of said bifurcated link, whereby said switch blade will be rotated axially upon its pivotally mounted support when said bifurcated link and said operating arm operate in said first range of movement of the crank arm and be subsequently swung with its pivotally mounted support out of cooperating relation with said stationary contact when said bifurcated link and said operating crank arm operate in said second range of movement of the crank arm.

3. A disconnecting switch operating mechanism, comprising in combination a pivotally mounted support, a switch blade carried by said pivotally mounted support and adapted to turn about its longitudinal axis, a stationary contact, a rotatable operating shaft positioned in spaced relation with said pivotally mounted switch blade support, an extending crank arm at the end of said operating shaft adapted to move through an arc in a plane at right angles to the plane of the swinging movement of said switch blade, a swivel at the outer end of said crank arm having oppositely extending trunnions, an arm attached to and extending radially from the longitudinal axis of said switch blade, and a bifurcated link hingedly connected at its extending end to the arm upon said switch blade and having its bifurcated end journaled upon the oppositely extending

trunnions carried by said swivel, whereby said bifurcated link will form a substantially rigid extension of said crank arm and turn the switch blade about its longitudinal axis as the crank arm moves through and adjacent its dead center relation with respect to the longitudinal axis of said switch blade and subsequently hinge with respect to said crank arm about said trunnions as the crank arm moves through the remainder of its arc of movement to thereby effect a swinging movement of the switch blade between its closed and open circuit positions.

4. A disconnecting switch operating mechanism, comprising in combination a pivotally mounted support, a switch blade carried by said support and adapted to be turned about its longitudinal axis and swing in a vertical plane, a rotatable operating shaft positioned in spaced relation to the pivotal axis of said pivotally mounted support, a crank arm at the end of said shaft adapted to move through an arc in a plane at right angles to the plane of the swinging movement of said switch blade, a swivel at the outer end of said crank arm having transversely extending trunnions, an arm attached to and extending upwardly from said switch blade, and a bifurcated link connected at one end through a universal connection to the arm upon said switch blade and having its bifurcated end journaled upon the transversely extending trunnions carried by said swivel, whereby said bifurcated link will form a substantially rigid extension of said crank arm and turn the switch blade about its longitudinal axis as the crank arm moves through and adjacent its dead center position with respect to said pivotally mounted support and subsequently hinge with respect to said crank arm at said trunnions to thereby effect a swinging movement of the switch blade between its closed and open circuit positions as said crank arm moves through the remainder of its arc of movement.

5. A disconnecting switch operating mechanism, comprising in combination a pivotally mounted switch blade support, a switch blade carried by said support, adapted to be turned about its longitudinal axis and swing in a vertical plane into and out of cooperating relation with a stationary contact, a rotatable operating shaft positioned in spaced relation to the pivotal axis of said pivotally mounted switch blade support, a crank arm carried by said operating shaft adapted to move through an arc in a plane at right angles to the plane of the swinging movement of said switch blade, a swivel at the outer end of said crank arm, a clevis-like member extending radially from said switch blade, and a link connected at its extending end through a universal connection to the clevis-like member upon said switch blade and having its other end journaled upon said swivel in a manner to form a substantially rigid extension of said crank arm which will turn the switch blade about its longitudinal axis as the crank arm moves through and adjacent its dead center position with respect to said pivotally mounted switch blade support and subsequently hinge with respect to said crank arm to thereby effect a swinging of the switch blade between its closed and open circuit positions as said crank arm moves through the remainder of its arc of movement.

JOHN B. SHAW.
